UNITED STATES PATENT OFFICE

2,467,389

FORCE-LASTED SHOE AND METHOD OF
MAKING IT

Jacob Simon Kamborian, West Newton, Mass.

Original application September 22, 1943, Serial
No. 503,336. Divided and this application May
1, 1947, Serial No. 745,285

5 Claims. (Cl. 36—19.5)

1

This invention relates to the manufacture of footwear, the present application being a division of my application of Letters Patent, Serial No. 503,336, filed September 22, 1943, for Manufacture of footwear, now Patent No. 2,446,286, granted August 3, 1948. While in certain aspects the invention is of broader utility, it is more particularly concerned with the manufacture of the so-called "slip lasted," "California," "platform" or "force-lasted" type. In this type of shoe the usual stiff inner sole is omitted and replaced by a thin, soft and flexible sole element (commonly termed the "sock lining" in this type of shoe) customarily of textile fabric and which is stitched directly to the upper prior to lasting. A middle or platform sole, usually comprising a thick, soft and cushion-like elements, semi-sole or "platform" is cemented to the under side of the sock lining, and an outer sole is cemented to the under surface of the middle sole. The upper is provided with a skirt portion, "extension," "platform" or "wrapper" of flexible material which continues downwardly from approximately the level of the sock lining, and which covers and protects the edges of the middle sole, the lower margin of the wrapper being interposed between the middle and outer soles.

One object of the invention is to provide a force-lasted shoe wherein the seam which unites the upper and sock lining is disposed inwardly of the edge of the platform or middle sole in the completed shoe. A further object is to provide a force lasted shoe wherein portions of the wrapper constitute respectively a lasting allowance and a platform cover. A further object is to provide a method of making force-lasted shoes wherein the upper material, after assembly with the sock lining and wrapper, and after the introduction of the last, is subjected to lasting stress. These and other objects and advantages of the invention will be pointed out more fully in the following, more detailed description and by reference to the accompanying drawings wherein.

Fig. 1 is a perspective view of a shoe upper comprising a wrapper of novel construction and having the sock lining secured to the wrapper;

Fig. 2 is a fragmentary transverse section through the forepart portion of the upper of Fig. 1, showing the arrangement of the sock lining, upper and wrapper during the formation of the uniting seam, a portion of the sock lining being broken away to show the last; and

Fig. 3 is a fragmentary transverse section, to larger scale, through the forepart portion of a

2

lasted shoe of the kind shown in Fig. 1, the middle and outer soles being attached.

Referring to the drawings the numeral 1 designates the upper of a shoe which, in Fig. 2, is shown mounted upon a last 2. This upper comprises an outer element 1^a which may be of leather, fabric or the like, and a lining 1^b. The lining 1^b is cut with but little lasting allowance and is secured by the stitched inseam 6 to the margin of a sock lining 5. The sock lining may be of any suitable material but is usually quite thin, as compared with the conventional insole. Usually this sock lining or thin flexible insole is of textile fabric or the like.

The wrapper strip 7 may be of any suitable material, for example like that of the outer element 1^a of the upper, or of a different material. For example if the outer member 1^a be of leather the wrapper strip 7 may be of textile fabric or vice versa.

In uniting the upper wrapper and sock lining they are disposed as illustrated in Fig. 2 so that the marginal portion of the upper surface of the insole or sock lining and the outer surface of the wrapper or platform cover 7 lie next to the inner and outer surfaces respectively of the upper comprising the parts 1^b and 1^a. The inseam stitching 6 may unite the wrapper to the upper but as here illustrated a separate seam 6^a unites the wrapper to the upper; the row of stitches constituting the seam 6^a extending along the wrapper intermediate and substantially midway between the opposite edges of the latter, thereby defining two flaps 7^e and 7^f of substantially equal width. The upper flap 7^e functions like the usual wrapper or platform cover while the lower flap 7^f extends down below the inseam 6 and constitutes, in effect, an extension of the upper, functioning as the customary lasting allowance provided in making shoes of conventional type.

After the upper, sock lining, and wrapper have been stitched together, the flap 7^f is employed like the lasting allowance in conventional shoes in applying stress to the upper material, this stress being so directed as to tend to draw the seam 6 over the bottom of the last. This flap 7^f or lasting allowance is then secured by adhesive to the under surface of the insole or sock lining 5. The middle or platform sole 11 is now put in place and cemented to the bottom of the sock lining and the other flap 7^e of the wrapper is drawn down about the edges of the middle or platform sole and its free margin is secured to the under side of the middle or platform sole, for example

by adhesive. The outer soles S' is then attached in any desired manner.

While the single inseam 6 may, as suggested, constitute the sole means for uniting the sock lining, upper and wrapper, it is preferred, as above described, to employ a plurality of seams.

While the term "force-lasted" has herein been adopted as an accurate and complete designation, it is to be understood that this term describes any article of footwear of the so-called "California," "platform," "slip-lasted" or similar type.

It is to be understood that the invention is not necessarily limited to the precise arrangement or procedure above disclosed but is to be regarded as broadly inclusive of any and all modifications falling within the scope of the appended claims.

I claim:

1. The method of making a shoe which comprises stitching together a sock lining, an upper and a wrapper strip, the stitches which unites the wrapper strip and upper extending lengthwise of the wrapper strip intermediate the edges of the latter, thereby defining a lower wrapper flap designed to constitute a lasting allowance, and an upper wrapper flap designed to constitute a platform cover, inserting a last into the upper, last-in the lower flap of the wrapper strip over the bottom of the sock lining and adhesively securing it in place, applying a platform sole to the bottom of the sock lining, drawing the cover flap of the wrapper down about the edge of the platform sole, and uniting its margin to the under surface of the platform sole.

2. The method of making a shoe which comprises stitching together a sock lining, an upper and a wrapper strip by an inseam which extends lengthwise of the wrapper strip intermediate the edges of the latter, thereby defining upper and lower wrapper flaps, inserting a last into the upper, applying stress to the lower wrapper flap such as to draw the inseam inwardly over the bottom of the last, securing said lower flap to the under surface of the sock lining, applying a middle sole to the under surface of the sock lining, drawing the upper flap of the wrapper downwardly about the edge of the middle sole and securing its margin to the under surface of the middle sole, and applying an outer sole.

3. The method of making a shoe which comprises stitching together a sock lining and an upper, securing a wrapper strip to the upper by a row of stitches passing through the upper and wrapper strip, said row of stitches extending longitudinally of the wrapper strip substantially midway between its edges, thereby defining two wrapper flaps, the wrapper strip being so assembled with the upper, prior to uniting them, that the outer surface of the wrapper strip contacts the outer surface of the upper and so that one of the flaps of the wrapper extends downwardly beyond the seam which unites the upper and sock lining, introducing a last into the upper, applying stress to that flap of the wrapper which extends down below the seam uniting the upper

and sock lining so as to draw the latter seam inwardly over the bottom of the last, adhesively securing the last-named wrapper flap to the under surface of the sock lining, securing a middle sole to the under surface of the sock lining, drawing the other flap of the wrapper downwardly and about the edge of the middle sole and securing its margin to the under surface of the middle sole, and applying an outer sole.

4. A shoe having an upper and a sock lining, the upper comprising an outer element and a lining, a seam uniting the lining and sock lining, a flexible wrapper strip secured to the upper by fastening elements extending longitudinally of the wrapper strip substantially midway between its edges so as to define marginal flaps extending in opposite directions from said row of fastening elements, the marginal portion of the upper surface of the sock lining and the outer surface of the wrapper being next to the lining and outer element, respectively, of the upper, one of said marginal flaps of the wrapper underlying and being adhesively secured to the sock lining, a middle sole having its upper surface, intermediate the edges of said latter flap, contacting and adhesively attached to the sock lining, the other flap of the wrapper strip embracing the edge of the middle sole and having its free margin underlying the middle sole, and an outer sole united to the middle sole.

5. A shoe comprising an upper and a sock lining, the margin of the sock lining being folded under to provide two plies, the lower edge portion of the upper underlying and contacting the lower ply of the margin of the sock lining, a strip of flexible material having its midportion underlying and contacting the under-surface of the edge portion of the upper, a row of fastener elements extending longitudinally of the flexible strip substantially midway between its edges so as to define marginal flaps extending in opposite directions from the row of fastener elements, said fastener elements uniting the strip to the edge portion of the upper, a second row of fastener elements uniting the edge portion of the upper to the lower ply only of the margin of the sock lining, one flap of the strip extending inwardly beyond the edges of the upper and of the lower ply of the margin of the sock lining and being anchored to the upper ply of the sock lining, a sole member underlying said inwardly extending flap, the outer flap embracing the edge of the sole member, and means connecting said latter flap to the sole member.
